BOBBIN

Douglas Kay Seaborn, Pendleton, S.C., assignor to Deer-
ing Milliken Research Corporation, Pendleton, S.C.,
a corporation of Delaware

Application January 5, 1956, Serial No. 557,543

7 Claims. (Cl. 242—118.6)

This invention relates to bobbins for use in textile apparatus, and more particularly to a unique bobbin arrangement for over-end unwinding of yarn therefrom.

It is an important feature of this invention that standard cylindrical core dual flanged bobbins may be easily and quickly converted for use in a creeling operation where the yarn is unwound over one end thereof directly after twist winding of the yarn thereonto. And conversely, a creeling bobbin, when constructed according to my invention may be converted to a standard cylindrical core bobbin construction, if desired, by a few simple mechanical manipulations. Of course, it will be obvious that the creeling bobbin form might also be used similarly to conventional bobbins for roll-off unwinding, if so desired, although it will be readily apparent that it is much more desirable in most instances to convert the bobbin to standard cylindrical core construction for such use.

It is a further feature of this invention that provision is made for positively holding the original yarn end on the axially outer portion of the bobbin flange at the end of the bobbin opposite to that of a frusto-conical plug insert adjacent the opposite flange, so that a yarn transfer tail may facilely be formed at the end opposite to that over which the yarn is to be taken off, the frusto-conical insert serving to permit filling of the bobbin along its entire length and pulling of the yarn off over the end having the insert thereat without breaking or otherwise damaging the yarn (as for instance, scuffing of the yarn due to excess tension rubbing, etc.).

These and other features and advantages of the invention will readily become apparent to one skilled in the art from a reading of the following detailed description, taken in conjunction with the accompanying drawings, wherein

Figure 1 is a view in perspective of a physical embodiment of my invention;

Figure 2 is a side elevation view in partial section illustrating one construction of the embodiment of Figure 1;

Figure 3 is an end view of the embodiment of Figure 1, illustrating the upper end of the bobbin of Figure 2;

Figure 4 is a partial view in diametral section of a modified form of the invention;

Figure 5 is a partial view in diametral section of another modified form of the invention;

Figure 6 is a partial side elevation illustrating a further modification.

Referring now to the figures of the drawing, as seen in Figure 1, there is provided a bobbin 10 having a substantially cylindrical core or barrel 12 of wood or the like and two planar end flanges 14 and 16 of pressed fiber or plastic. End flange 14 is suitably secured to the core or barrel 12 as by a plurality of headed screws 18, and serves as the supporting end during winding of yarn onto barrel 12.

On the axially outer surface of flange 14 a pair of double ended yarn clips 20 are secured, as by small screws or nails 22, and serve to secure the transfer tail of the yarn. In order to provide a sufficiently long transfer tail

2

the circumferential periphery of flange 14 has an annular groove 24 formed therein, around which a few turns of yarn are wound after securing the yarn end to a clip 20 and prior to filling the bobbin between the two end flanges 14 and 16. To facilitate passage of the yarn into and out of the groove 24 (i.e. from clip 20 into the groove 24 and thence circumferentially along the groove and out onto the core of barrel 12) a longitudinal slot 26 is formed in the peripheral rim of flange 14 adjacent each clip 20.

Barrel 12 and flange 14 have formed therein a central hole or bore 30 for receiving a driving shaft or spindle (not shown). A transverse key slot 28 may suitably be formed in the flange 14 as shown in Figure 1, in accordance with conventional practice, for receiving a key or locking member on the driving spindle whereby the bobbin may be locked to and driven by the spindle. In order to prevent oscillatory or vibratory movement of the bobbin on the drive spindle a metal or other suitable bushing 32 may be fitted within the bore 30 of the bobbin, as shown, which when the bobbin is in position on the drive spindle engages the upper end thereof in close relation.

At the upper end of the bobbin, flange 16 is secured to the barrel 12 through the medium of screws 34 which extend through countersunk holes therefor in the flange 16 and into the end of barrel 12.

A frusto-conical plug insert 36 of hard rubber, plastic or other suitable material, having a bore complementary to the outer surface of the cylindrical barrel 12 is mounted on the barrel with its planar base extending into closely adjacent relationship to the inner planar surface of flange 16. Preferably, a sheet 38 of soft felt material is disposed between flange 16 and the base of insert 36 and extends out slightly beyond the periphery of the base of insert 36 in order to prevent the catching of yarn between the flange and the insert. Likewise, a similar sheet 42 of felt material of slightly larger size than the cross-section of barrel 12 is disposed between the barrel 12 and the flange 14 to prevent the catching of yarn in this joint.

Referring now to Figures 2 and 3, insert 36 is removably held firmly in contact with felt sheet 38 and in close adjacency to flange 16. To this end a pair of diametrically spaced headed screws 40 extend through recessed holes therefor in flange 16, thence through holes in sheet 38 and threadedly engage the base of insert 36, whereby the insert is securely held in position and may readily be removed from barrel 12 by removal of flange holding screws 34. If it is also desired to remove the insert from the flange 16, it is only necessary to additionally remove insert holding screws 40. The insert 36 may thus be added, replaced, or removed simply, easily and quickly.

The function of insert 36 is to permit a complete filling of the bobbin along its entire length between flanges 14 and 16 while permitting the yarn to be drawn off over the end of the bobbin around flange 16, as in a creeling operation, without the yarn becoming broken or otherwise damaged as it is unwound from the windings lying near the flange 16. In the standard cylindrical barrel bobbin having only planar faced end flanges the top few layers of yarn may be wound off over the end; however, when the lower layers of yarn are reached the combined effects of sharp bending of the yarn and friction thereon along the inner surface of the end flange as the yarn is unwound from the windings adjacent the let-off end flange will cause the yarn to break or become otherwise damaged, particularly in the case of synthetic yarns such as rayon, nylon, etc. By the provision of this plug insert arrangement a standard bobbin may readily be adapted for use in drawing off over the end thereof widely varied denier synthetic or other yarns directly after twist-winding or other direct winding thereonto.

In order to achieve maximum results according to my

invention it is necessary that the angle of flare α from the smaller end of the peripheral surface of plug insert 36 toward its base be equal to, or preferably smaller than, the angle of flare β from the smaller end of the plug to the peripheral surface of the end flange 16.

It is more advantageous for angle α to be smaller than angle β rather than merely equal thereto in order to assure absence of rubbing contact between the yarn and the peripheral surface of the plug 36 after it leaves its wound-on position on the plug, and also to permit the holding of greater amounts of yarn on the bobbin for any given diameter of filling thereof while still achieving the function of yarn let-off over the end of flange 16 with substantially no damage to the yarn. However, in order to prevent yarn damage it is important that the difference between angle α and angle β be not greater than approximately $\beta/4$ degrees. On the other hand, in order to achieve maximum yarn capacity with substantially no yarn damage the angle β must be as large as possible. In one specific example constructed according to my invention, a bobbin having a barrel diameter of 1.75 inches and a diameter of 5 inches for end flange 16 has functioned with maximum results in handling nylon and rayon yarns of widely varied deniers by employing a plug insert 16 having a one inch axial length and an angle of flare α of approximately 52 degrees. The angle β in this case is thus approximately 58 degrees with $(\beta - \alpha)$ being approximately 6 degrees.

It has further been found that yarn damage may still be held to a minimum in most instances with an even further increase in the yarn capacity of the bobbin by shaping the base of plug 36 to form a rim, as indicated at 44. Most satisfactory results have been achieved with rims of width up to approximately .3 inch, the rim in the specific example given above being .12 inch.

It will be noted that in the use of a bobbin according to this invention the yarn is first wound onto the bobbin with the transfer tail secured under and around one of the clips 20, thence into groove 24 and around the periphery of flange 14, the bobbin then being filled with yarn along its entire length between flanges 14 and 16 to a diameter or depth which may, if desired, extend out beyond the outer periphery of the base of insert 36. The yarn may then be unwound over the smooth rounded peripheral surface of end flange 16 for its desired further use, as for instance the winding thereof onto a warp beam, etc. from a creel or other suitable support. By thus disposing the insert 36 at the opposite end to the tail retainer clips 20, the tail secured by a clip 20 may be unloosened therefrom and attached to the extending end of a succeeding bobbin whereby an effective and convenient transfer tail arrangement is formed which does not in any way interfere with the yarn being drawn off the bobbin over the let-off flange 16 at the opposite end of the bobbin.

In a modified form of the invention, as illustrated in Figure 4, the insert 36a is formed with a lip or shoulder 46 extending radially inward at its base, to form an inner or central aperture preferably complementary to the outer periphery of bushing 32. The flange 16a may be secured to barrel 12a in a similar manner to the securing of flange 16 in the embodiment of Figures 2 and 3, as by a plurality of flat headed screws 34a. In this embodiment, however, with the lip or shoulder 46 extending across the end of barrel 12a the screws 34a either threadedly engage or, preferably, pass through suitable holes formed in the lip or shoulder 46, and thus serve to more firmly anchor the insert 36a against possible movement, particularly possible rotary movement relative to barrel 12a and flange 16a. It will readily be apparent that axial movement of insert 36a relative to barrel 12a is prevented in this embodiment by the lip or shoulder 46 which rests between the end of the barrel 12a (which end thus forms a complementary abutting shoulder) and the inner face

of felt 38a. If desired, an additional screw or screws 40a may be employed in a manner similar to that shown in Figures 2 and 3 to prevent torsional stresses on lip or shoulder 46, but for most practical purposes such is not necessary.

In a further modification as shown in Figure 5 the barrel 12b is recessed along its end to form a stepped shoulder 56 against which abuts a substantially complementary shoulder 58 formed on the reduced or small end 10 of insert 36b. The insert 36b is thus effectively held against relative axial movement on barrel 12b by this abutting shoulder arrangement. The insert 36b tends to be restrained against relative rotational movement on barrel 12b by the frictional resistance between its base 15 and felt sheet 38b and its shouldered small end 58 and shoulder 56 as well as along its central bore with its frictional engagement with the reduced outer surface of barrel 12b. While this frictional resistance alone may be sufficient in some instances to prevent rotation of the insert 20 36b on the barrel 12b, it is preferable in most cases to employ additional means in the form of one or more screws 40b, as shown, or a complementary key and slot arrangement between the barrel and insert, to positively prevent any slip of the insert about the barrel. If it is 25 desired to use the embodiment of Figure 5 as a standard cylindrical barrel bobbin with no insert, such may readily be accomplished by slipping over the reduced end portion of barrel 12b a sleeve (not shown) of suitable material, such as hard rubber or the like, and having a thickness corresponding to the depth of the shoulder 56 formed on barrel 12b, with the length thereof corresponding to the length of the reduced portion of the barrel.

Each of the embodiments of Figures 2, 4 and 5 has been illustrated with an insert 36 having a rim 44 formed at the outer periphery of its base, and such is the preferred construction for reasons as pointed out supra. However, alternatively, the arrangement of any one of the embodiments of Figures 2, 4 or 5 might also be employed with a frusto-conical insert 36c having a continuous unbroken tapered surface, if desired, with consequent elimination of the advantageous results achieved with use of the rim 44, and still retain most of the major features of the invention.

Obviously, various modifications will be apparent to those skilled in the art without departing from the scope or teaching of my invention, and I, therefore, do not intend the invention to be limited except as defined by the scope of the appended claims.

Having described my invention, I claim:

1. A bobbin comprising a barrel having a flange at each axial end thereof, one of said flanges having a planar axially inner face, a frusto-conical plug having a central aperture complementary to the peripheral end portion of said barrel inwardly of and adjacent said one of said flanges, said plug being mounted on said end portion with its base extending toward and in close adjacency to said planar face of said one flange, a soft fiber sheet disposed between and in contiguous relation to said planar face of said one flange and the base of said plug, said sheet being of slightly larger circumference than the circumference of the base of said plug.

2. A bobbin comprising a barrel having a flange at each axial end thereof, one of said flanges having a planar axially inner face, a frusto-conical plug having a central aperture complementary to the peripheral end portion of said barrel inwardly of and adjacent said one of said flanges, said plug being mounted on said end portion with its base extending toward and in close adjacency to said planar face of said one flange, at least one headed screw extending into removably securing relation through said one flange and into the end of said barrel, and at least one separate headed screw extending through said one flange and into said plug at a radial position beyond the outer peripheral surface of said barrel whereby said plug

is secured to said one flange independent of the screw securing said one flange to said barrel.

3. A dual purpose, dual structure bobbin comprising a cylindrical barrel having a planar disk-like annular flange at each axial end thereof, at least one of said flanges being removably secured to said barrel, a frusto-conical plug having a central aperture complementary to the peripheral surface of said barrel adjacent the end of said barrel having said one flange removably secured thereon and being removably mounted in contiguous surrounding relation on said barrel, a soft felt sheet disposed in contiguous relation to the axially inner face of said one flange, said sheet being of larger diameter than the diameter of the base of said plug and of smaller diameter than the diameter of said one flange, the base of said plug being in contiguous relation to the opposite surface of said sheet, said plug having an annular peripheral rim formed at its base, at least one headed screw extending through said one flange and into securing relation with said barrel, at least one headed screw extending through said one flange and into securing relation to said plug at a radial point beyond the outer periphery of the adjacent end of said barrel, the other of said flanges having a yarn tail retainer on its axially outer surface.

4. A bobbin according to claim 3 wherein said plug and said barrel have adjoining shoulders extending transverse to the barrel axis and holding said plug against axially inner movement beyond the position in which said shoulders contact one another.

5. A bobbin according to claim 3 wherein the angle of flare α from the smaller end of the peripheral surface of said plug is smaller than the angle of flare β from the smaller end of the peripheral surface of said plug to the peripheral surface of said one flange, said plug having an annular peripheral rim formed at its base, the width of said rim being within a range of from greater than zero up to approximately .3 inch, said angle β being not substantially greater than approximately 65 degrees, and the difference between said angles β and α being not substantially in excess of approximately $\beta/4$ degrees.

6. A bobbin comprising a barrel having a flange at each axial end thereof, one of said flanges having a

planar axially inner face, a frusto-conical plug having a central aperture complementary to the peripheral end portion of said barrel inwardly of and adjacent said one of said flanges, said plug being mounted on said end portion with its base extending toward and in close adjacency to said planar face of said one flange, at least one headed screw extending into securing relation through said one flange and into the end of said barrel, and additional securing and sealing means fastening said plug to said one flange independently of said screw securing said one flange to said barrel.

7. A bobbin according to claim 6 wherein said barrel has a reduced cylindrical portion at said one end and forming an annular shoulder at the junction thereof with the remainder of said barrel, said portion having a length corresponding to the axial length of said insert, said insert having a shoulder at its smaller end, said insert shoulder having a radial depth corresponding to the depth of said barrel shoulder, said end shoulder on said insert fitting in contiguous relation with said shoulder on said barrel.
